CLAIM

The ornamental design for “a portion of a navigation/player tracking/payment panel for a gambling unit,” as shown and described.

DESCRIPTION

The sole FIGURE is a front view of a portion of a navigation/player tracking/payment panel for a gambling unit in accordance with my design.

The dashed lines shown in FIG. 1 represent environmental structure and form no part of the claimed design. The dotted lines shown in the FIGURE represent the borders between claimed subject matter and unclaimed subject matter and form no part of the claimed design.
